UNITED STATES PATENT OFFICE.

JAMES MORRISON, OF CINCINNATI, OHIO, ASSIGNOR TO THE HIGHLAND BODY MANUFACTURING COMPANY, OF CINCINNATI, OHIO, A CORPORATION OF OHIO.

VEHICLE BODY DOOR.

Application filed June 23, 1922. Serial No. 570,397.

My invention relates to sliding doors for vehicle bodies and more generally to closures for vehicle cabs.

In my Letters Patent in the United States No. 1,451,626, dated April 10, 1923, I have described and shown a form of window for vehicle bodies and cabs, in which the window has a combination of sliding and folding motions, which permits of its entire removal from the open sides of the cab, leaving all but a partially cut-away panel as the only lateral closure of the cab.

The present invention deals more particularly with a sliding door, which enters a well formed in the side panel of the cab, thereby permitting the door also to be entirely withdrawn except for the side panel. This door is adapted particularly for use with the sliding and folding window construction of my said application.

In connection with the door I have provided for a mounting and guiding means which maintains a tight, non-rattling fit, with compression spring take up and with the wear faces between the moving parts adapted for a natural even wear, without developing looseness at any one point.

When closed I provide for the door an automatic means for maintaining a tight fit against the dash side panel, and when moved into the pocket or well, I provide for the door an automatic means for forcing it into a tight fitting position.

In the locking mechanism I provide an automatic or spring lock having a handle which is likewise used for manipulating the door, and which folds down behind the inside pillar of the well when the door is open.

In various other ways, as will be noted, I provide the door with means whereby its motion is easy but its fit and position at all times is secure and non-rattling.

These objects and advantages I accomplish by that certain construction and arrangement of parts to be hereinafter more specifically pointed out and claimed.

In the drawings,

Figure 1 is a front elevational detail showing the door edgewise and in the side panel well.

Figure 2 is a section taken vertically through the door on the line 2—2 of Figure 6.

Figure 3 is a detail vertical section on a larger scale showing the spring plunger on

the top of the door in position in the side panel well on line 3—3 of Figure 6.

Figure 4 is a detail plan view of the joint between the door and the dash side panel column.

Figure 5 is a perspective section showing the spring clamp and the track and roller.

Figure 6 is a side elevation of the door located on the sill of the cab with the track partly removed to show the locking points.

Figure 7 is a side perspective view of the cab showing the door closed and the sashes of the window withdrawn on one side.

Figure 8 is a perspective view of the entire cab showing it fully open.

Figure 9 is a perspective section taken vertically through one of the window sashes adjacent the front edge thereof.

The cab as shown is made up of a top 1, side panels 2, a dash 3 and a dash side panel 4. Each side panel is formed with a well 5 of a depth to take the door and opening forwardly. The top 6 of the well extends rearwardly inside of the side panel and alongside of this top wall a guide channel 7 for the window is formed. The top wall of the well is formed so as to slope downwardly and outwardly.

The front panel 4 terminates rearwardly in a column having a sloping face 8 directed inwardly of the cab.

The floor of the cab comprises sills 9 which extend back forming the bases of the two wells, and erected on the outer sides of the sills are tracks made up preferably of metal bars 10 turned on edge. Beneath each sill is placed a strip 11 having its outer face about flush with the track bar and having its under face slanting inwardly and upwardly.

In the sill are located the desired holes or socket plates 12 for the door lock, one being closely adjacent the dash side panel and one adjacent the mouth of the well at each side of the structure.

The doors are formed with framework pieces covered with sheet metal with the supporting rollers and clamp mechanism set in gains in the frame and covered by the plates.

The vertical frame pieces of the doors I have indicated as 13, the top pieces as 14 and the bottom pieces as 16. There may also be cross braces as desired. The outside plates 17 forming a complete facing for the door

frames may be mounted thereon in any desired way and over the top is set a plate 18, while at the front there will preferably be another metal plate 19.

5 The top of the door frame and also the plate covering it are arranged at a slant facing downwardly and outwardly, while the front frame piece of the doors, together with its facing, if any, slants inwardly and forwardly.

I provide in the top of the door frame a narrow space between the top frame piece and the metal binding 14^a, in which is set a strip of spring steel 15^a having a bifurcated 15 end 16^a forming a bearing. This bearing lies in a pocket 17^a formed in the upper frame piece and binding. The bearing carries a roller 20 therein which lies in the well when the door is closed, and holds the 20 door frame up against the member at the inside wall of the mouth of the well. The strip 15^a, the roller and the pocket are on a slant similar to the top of the door.

Spring plungers 21 are mounted in the 25 rear of the door, so that when the door is thrust back into the well and locked, these plungers will bear against the rear wall of the well and hold the door tight between the lock and said wall.

30 A further set of said spring plungers are set, as shown at 22, in the dash side panel or column, so as to press inwardly on the slanting forward edge of the door.

Since the dash side panel is formed with 35 a flange or web 23 on its inner face, the door will be pressed against this flange by the plungers 22, thereby holding it tight at the front.

Set into gains in the base frame piece of 40 the doors are mounting plates 24 for rollers 25, which said rollers are grooved to ride on the rails or tracks 10. The facing plates of the doors cover these rollers from view, as has already been noted.

45 Set into a long gain 25^a in the forward frame piece of the doors are guide straps 26 mounting slidably a long bar 27, which acts to hold the door down to the track, prevent it from becoming displaced laterally, and

50 brings it to alignment with the track when it is dislodged. This bar has at its upper end a lip 28, and at its lower end a lip 29, said latter lip being bent so as to take a full bearing against the under face of the strip 55 11.

55 In a deeper gain or socket at the upper end of the gain 25^a is set a compression spring 30, which presses against the lip 28 and forces the bar upwardly, so that the lower lip on the bar will ride closely against the strip 11, thereby holding the door down tight with its rollers on the rail. As this lip and strip engagement is on an angle, there is no chance of the lips 28 becoming dislodged, and the wear will be even on the 60 strip 11.

The lock for the door comprises a jump bar 31 mounted in brackets 32 on the forward frame piece of the door at the inside thereof. A compression spring 33 mounted over the bar tends to force it down by engagement with a collar 34 thereon. At the top of the bar is pivoted a handle 35, which is mounted pivotally in the door frame in a countersunk fitting 36.

Thus the handle extends downwardly close 75 to the door when the jump bar is positioned in one of the holes in the sill, such that it will lie against the edge of the inner wall forming the well for the door without projecting and catching the driver's garments. 80 It will be further noted that the driver in operating the door from open position with the handle lying alongside the edge of the well, will grasp the handle and raise it, thereby lifting the jump bar from the socket 85 adjacent the well. He will then manipulate the door with the same handle and thrust it forward until the door contacts with the spring plungers on the dash panel, whereupon the release of the handle will permit 90 the jump bar to descend into the sill socket at this point.

The door will be held tightly when closed by means of the plunger devices at the front and by the plunger lying within the pocket 95 on the upper edge of the door, and at all times will be held down tightly by the hooked bar engaging the beveled under strip hitherto described.

Referring to the window devices it will be 100 noted that the windows are made up, as in my said application for patent already referred to, in three sections (preferably) as indicated at 50, 51 and 52. The sections 50 and 51 are hinged together in any desired 105 way. The sections 51 and 52 are hinged by means of leaves 53 and pintles which serve other purposes also.

Thus at the upper hinge, the pintles 54 have springs 55 holding them down and 110 hooked ends 56 riding over beveled strips 56^a set in the top of the vehicle.

The lower pintles 57 have rubber rollers 57^a on their under ends, which ride in the groove or channel located on the inside upper edge of the door well.

At the forward end of the section 50 and rear end of the section 52, these special pintle devices are used also, although in this instance they do not act as pintles.

The sections 52 and 51 will fold inwardly, so that the rear section may lie flat against the back of the cab with the section 51 lying in parallel position against it while the front section lies against the side panel of 125 the cab.

A handle 58 is used to lock the window in place into sockets in the top rail, and also to manipulate the window.

On the under edge of the window is a wip- 130

ing strip 59 which engages the top edge of the door, same slanting downwardly and outwardly, as has been noted. The top of the dash side panel may be provided with a channel at each side similar to the channels alongside of the door well.

5 There is not necessarily any connection between the doors and the windows except for the wiping strip, and except as they appear 10 in combination with the side panel construction of a cab.

The windows and doors both slide into concealment with relation to the side panel structure, so that a completely open or completely 15 closed cab may be provided, using no flexible frames, so that glass may be provided in the windows.

I do not wish to be limited to specific 20 structure in the claims that follow because of my failure to note, as the above description proceeded, these mechanical equivalents 25 that might be substituted for the parts named.

Having thus described my invention, what 25 I claim as new and desire to secure by Letters Patent, is:—

1. In combination with a vehicle cab having a top, side panels, a dash, and panels at the sides of the dash, a well formed in connection with the side panels, a support, a window formed in rigid, articulated sections and mounted so as to slide on the support and fold behind the vertical plane defined by the front edges of the side panels, a door 35 adapted to fill the space between the well and the dash panels, said door adapted to slide into the well, said window having means to engage the door to act as a weathering, and means for holding the window and door in place to close all space between the side 40 panels and dash side panels of the cab.

2. The combination with a vehicle cab having side panels, sills and a dash, means forming a well in a side panel, track forming 45 means on the sill, means on the door for holding it across the opening between the side panel and dash, and resilient means positioned between the top of the well and the top of the door to force the door into tight 50 position within the well when the door is positioned across said opening.

3. The combination with a vehicle cab having side panels and sills, means forming a well in a side panel, means on the sill for the door to ride upon, said door having an upper edge slanted outwardly and downwardly, said well forming means having its top edge slanting in the same manner, and spring means operating between the top of 60 the door and the top of the well adapted to press the door downwardly and inwardly, said means comprising a resiliently held roller set into the top of the door and so positioned as to lie within the well when the 65 door is closed.

4. In a vehicle cab, the combination of a door, an element on which the door will ride, means behind which the door will move, and a resiliently pressed bar on the door, and means beneath the said element, said bar 70 having means at its end to engage said means beneath said element to hold the door tightly down on the said element.

5. In a vehicle cab, the combination with track means and a door riding on said track, 75 means behind which the door will move, and a resiliently pressed bar on the door, and means beneath the track, said bar having means at its end to engage said means beneath the track to hold the door tightly down 80 on the track, said means beneath the track and on the bar having a slant inwardly and upwardly of the cab, for the purpose described.

6. In a vehicle cab, the combination with a 85 linear track, a door, rollers on the door engaging said track, means behind which the door will slide when opened, a resiliently pressed bar on the door, and a strip beneath the track, said strip being faced on its under side in a slant inwardly and upwardly of 90 the cab, and a hook on the bar bent in a like manner to engage said strip, for the purpose described.

7. In a vehicle cab, the combination with 95 a track, a door riding on said track, means behind which the door will slide when opened, a bar slidably mounted in the door, said bar having a flange or lug adjacent its upper end, a compression spring seated in 100 the door and arranged to impart upward pressure on said flange, and a hook on the bar to engage beneath the track.

8. In a vehicle cab, the combination with a track, a door riding on said track, means 105 behind which the door will slide when opened, a bar slidably mounted in the door, said bar having a flange or lug adjacent its upper end, a compression spring seated in 110 the door and engaging from beneath said flange, a strip beneath the track, and a hook on the bar to engage said strip, said strip and hook being bent inwardly and upwardly, for the purpose described.

9. In a vehicle cab, the combination with a 115 well, a sill, a door adapted to slide into the well and ride on the sill, a dash panel, and means to resiliently hold the door down against the sill and resiliently press it away from the top of the well, when closed against 120 the dash panel and further means to resiliently press it inwardly at the dash panel, said panel having a projection against which said door is pressed.

10. In a vehicle cab, the combination with 125 a door, said cab having an opening adapted to be closed by said door, means for slidably supporting the door in the cab, means against which the door abuts when closed, said means and the door having abutting faces which 130

slant inwardly and forwardly of the cab, and resilient means adapted to lie between the said faces when the door is closed, and a projection against which the inner edge of the door is pressed by said resilient means.

11. In a vehicle cab, the combination with a door, said cab having an opening adapted to be closed by said door, means for slidably supporting the door in the cab, means against which the door abuts when closed, said means and the door having abutting faces which slant inwardly and forwardly of the cab, and resilient means adapted to lie between the said faces when the door is closed, and a projection against which the inner edge of the door is pressed by said resilient means, said resilient means comprising a spring plunger set into the door.

12. In a vehicle cab, the combination of a door, an element beneath the door on which the door will ride, means behind which the door will move, and resilient means on the door engaging the cab beneath the element on which the door rides, and adapted to hold the door down on said element, and to align the door with said element.

13. In combination with a vehicle cab hav-

ing a top, seat dash, floor and side panels extending alongside the seat, leaving a space to be closed and opened, a sliding door supported at the floor of the cab, and resiliently held to the floor, a pocket at the side panels into which the door will slide, said door adapted when closed to fill the space between the pocket and dash, an overhead support, a window in a plurality of sections mounted on and adapted to take positions on said support of closure of the space above the door and between the side panels and dash, and of nesting behind the vertical plane defined by the forward edges of the side panels.

14. In a vehicle cab, the combination of a door, a support on which the door rides and located beneath it, a well for said door serving to hold one end thereof when the door is closed and to house the door when the door is open, and a bar on the door having a hooked end, spring means exerting stress between the bar and the door, and said support including a member to engage said hooked end of the bar, holding the door down on the support.

JAMES MORRISON.
